(57) **CLAIM**

I claim the ornamental design for a tent top, as shown and described.

DESCRIPTION

FIG. 1 is a top, left side, front perspective view of a tent with a tent top illustrating the design

FIG. 2 is a top, left side, front perspective view of the tent top;

FIG. 3 is a right side view thereof;

FIG. 4 is a front side view thereof;

FIG. 5 is a rear side view thereof;

FIG. 6 is a left side view thereof;

FIG. 7 is a top plan view thereof;

FIG. 8 is a top, left side, rear perspective view thereof; and, FIG. 9 is a cross-section view thereof, along the line 9-9 in FIG. 7.

The broken lines shown represent environment only and form no part of the claimed design.

The surface shading lines are provided to indicate three-dimensional surface contour or curvature.
